UNITED STATES PATENT OFFICE.

THOMAS P. GREGER, OF PHILADELPHIA, PENNSYLVANIA.

DESIGN FOR A MANHOLE-COVER PLATE.

SPECIFICATION forming part of Design No. 30,812, dated May 16, 1899.

Application filed April 22, 1899. Serial No. 714,118. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for a Manhole-Cover Plate, of which the following is a specification, reference being had to the accompanying drawings, forming part thereof, in which—

Figure 1 is a top or plan view of a manhole-cover plate, showing the design of my invention. Fig. 2 is a central sectional view thereof, and Fig. 3 is an underneath plan view of said cover-plate.

The three views are deemed necessary or essential for the proper illustration and full understanding of the scope and character of my design.

As illustrated in the drawings, the leading or material feature of my design consists of the outline or configuration of the cover-plate, as well as the surface ornamentation thereof. As seen in top or plan view the cover-plate presents the appearance of a plain circular field a , inclosing at about the center an upwardly-projecting ring-shaped ornament b . When viewed in cross-section, the periphery of the field a is rounded, as at a' , and slightly hook-shaped. The upper face of field a slopes or inclines upwardly from the periphery to the central ornament b , into which it abruptly merges, as at b' . The under surface of the

field a , which constitutes the base of the cover-plate, is annularly grooved or channeled, as at d , adjacent to the rounded periphery a' , and has a downwardly-projecting annular ridge or rib d' , which in cross-section is triangular, or substantially so. From the rib d' to a central circular and downwardly-projecting ornament d^2 the base slopes upwardly, as at d^3 , the sloping base merging abruptly into both the rib d' and ornament d^2 , as at d^4 and d^5 . From the slanting base d^3 to the central ornament d^2 extend the triangular ribs e , which merge at one end into the base d^3 and incline upward therefrom until they merge into said ornament d^2 . When viewed in underneath plan, the cover-plate presents the appearance of three concentric rings a' , d , and d' , inclosing a circular field d^3 , within which field is located a circular ornament d^2 , from which radiate the ribs e .

Having thus described my invention, what I claim as new, and desire to secure by Letters Patent, is—

The design for a manhole-cover plate, substantially as illustrated and herein described.

In testimony whereof I have hereunto set my signature in the presence of two subscribing witnesses.

THOMAS P. GREGER.
